SEBASTIAN A. LOFTUS AND THOMAS CURETON, OF DAYTON, OHIO; SAID LOFTUS AS-SIGNOR TO SAID THOMAS CURETON AND SAMUEL CURETON, OF PLYMOUTH, OHIO.

SAND AND GRAVEL WASHER.

Application filed October 31, 1921. Serial No. 511,619.

This invention relates to machinery for separating materials, and more particularly to that type of machinery known as sand and gravel washers.

One of the principal objects of the invention is to provide apparatus for the washing, screening and separating of sand and gravel, and similar material, which is efficient, easy of operation and maintenance, and simple in its construction.

Other objects and advantages of the invention will be apparent from the description thereof set out below, when taken in connection with the accompanying drawing.

In the drawing, in which like characters of reference designate like parts throughout the several views thereof:

Fig. 1 is a view, partly in elevation and partly in section, of a sand and gravel washer embodying the invention;

Fig. 2 is a plan view of the apparatus shown in Fig. 1;

Fig. 3 is a sectional view along the line 3-3 of Fig. 1, looking in the direction of the arrows;

Fig. 4 is a view in elevation of one of the buckets forming a part of the apparatus, the view being in the direction of the arrow shown in Fig. 5;

Fig. 5 is a sectional view through the buckets shown in Fig. 4, along the line 5-5 thereof, looking in the direction of the arrows;

Fig. 6 is a sectional view through the apparatus along the line 6-6 of Fig. 1.

While this invention is generally applicable to the separating of materials, for purposes of description, and as setting out a preferred embodiment thereof, it is shown in connection with apparatus particularly designed for the separation of sand and gravel. It is a general practice to subject sand and gravel to an agitating and washing action to remove the dirt therefrom, after which the sand and gravel is screened. And the apparatus illustrated and described herein is an improved form of apparatus for carrying out this method of separation.

This apparatus comprises a rotatable drum 10, of sheet metal, or other suitable material.

One end of this drum has a head 11 secured therein, in which is provided an opening 12, through which the sand and gravel to be treated is introduced into the drum. The opening 12 is preferably surrounded by an inclined flange 13, and, inasmuch as this flange serves as the over-flow for the water introduced into the drum during the washing operation, it is made of such effective width that a suitable quantity of water is at all times present in the drum. Any desired type of apparatus for leading away the water which escapes over the lip of the flange 13 may be provided, and, since this particular part of the installed apparatus may be of any conventional character, no specific construction thereof is shown.

The sand and gravel to be treated is introduced into the rotatable drum 10 by means of the feed hopper 15, the sand and gravel being supplied to this hopper by hand, or by means of any suitable conveying apparatus. As illustrated in Figs. 1 and 2, this hopper has its lower wall 16 inclined at such an angle that the material introduced thereinto will readily slide along this lower wall, and this lower wall is extended, as shown at 17, to form a discharge spout, which, when the device is assembled, extends into the opening 12, so that material supplied to the hopper 15 will be discharged from this spout into the interior of the drum 10. In order to control the rate of discharge from the hopper, and to also control the positioning of the discharge spout relative to the water within the drum 10 this feeding apparatus is made adjustable. The upper portion of the hopper is provided with an arcuate slot 18, constructed to receive a supporting bolt 19, carried by an upstanding standard 20, the lower end of which is rigidly secured to one of the side members 21 of the frame upon which the entire apparatus is mounted. Extending transversely between the two members 20 is a cross bar 22, through which passes one end of the bolt 23, which is pivotally attached to the extension 24 carried by the lower end of the hopper or discharge spout, suitable adjusting nuts 25 being provided upon this bolt. A

double adjustment of the hopper and discharge spout is thus provided for. By varying the position of the supporting bolt 19 within the arcuate slot 18, the hopper may be 5 swung about the point of pivotal connection of the bolt 23 to the member 24 to increase or decrease the angle of inclination of the bottom 16, of this hopper. By proper manipulation of the adjusting nuts 25, the position of the bolt 19 within the arcuate slot 18 remaining constant, the lower end of the hopper may be swung about the bolt 19 as a pivot. By properly manipulating both of these adjustments the hopper may be moved 10 bodily without any variation in its angular positioning, or it may be moved both bodily and its angular positioning varied at the same time. This type of adjustment is particularly useful in that the angular positioning of the hopper may be varied as desired, and the positioning of the discharge spout relative to the water within the drum 10 at the same time so maintained as to minimize splashing due to the introduction of 15 the material into the drum.

Attached to the drum, and positioned interiorly thereof, are buckets 26, these buckets being arranged throughout the length of the interior of the drum in series of three. As 20 the drum rotates the material therein is caught up by these buckets, moved through the water in the lower part of the drum, to effect a washing of such material, and then carried upwardly in the buckets from which, 25 while the buckets are in elevated position, the material slides, being at the same time fed forward to bring it into the zone of the next succeeding series of buckets, where the operation is repeated. The material within the 30 rotatable drum is thus moved along the drum from one end to the other, being washed as it travels, so that dirt is separated from the sand and gravel, or whatever other material may be treated, the gravel being discharged 35 through one end of the drum, while the dirt or loam, originally admixed with the sand and gravel, is carried out through the other 40 end with the overflowing wash water.

The arrangement and construction of these 45 buckets 26 is clearly shown in Figs. 3, 4 and 5. As shown, in Fig. 3 the buckets are arranged around the drum at distances of substantially 120° from each other, three buckets being employed. Of course the number of 50 buckets in any series may be varied as desired, to suit any particular size of drum. Each of these buckets consists of two end plates 27, each of which is shaped to correspond with the curvature of the drum 10, and provided with cross pieces 28 and 29 which pieces are suitably curved and constructed for rigid attachment to the shell of the drum. As shown these buckets are 55 riveted to the drum, but other means of attachment may be used if desired. Also posi-

tioned between the end plates 27 is a plate 30 one edge of which terminates a considerable distance from the shell of the drum, to thus leave a free opening, designated generally by the numeral 31, within the bucket, the other end being extended beyond the end plates 27, and curled upon itself to form an inclined trough-like portion or spout, at that end of the bucket remote from the shell of the drum, and designated generally by the 60 numeral 32. Attached to the cross piece 29 is an upstanding flange or baffle 33, which extends entirely across the bucket. These buckets are so constructed and attached to the drum 10 that as the drum rotates the buckets are carried thereby. As shown in Fig. 3 the drum is in such position that one of the buckets is just reaching its lowest position. The construction of the buckets is such that as the drum rotates, carrying the 65 buckets through lower position, each bucket is free to pass through the water, and the sand and gravel contained therein, except for the baffle or flange 33. As the drum rotates this flange 33 carries the sand and 70 gravel with it through the water, which is free to pass over this baffle while the sand and gravel are not. A positive movement of the sand and gravel through the water is thus secured to give a maximum washing effect. As the drum continues to rotate the sand and gravel in advance of the flange 33 will be picked up thereby and carried upwardly until, as the rotation continues, it will drop off the flange 33 onto the member 75 30 whence, during further rotation, it will slide down into the inclined trough-like portion from which it will slide to fall back to the bottom of the drum. Thorough agitation of the sand and gravel is thus secured. As shown particularly in Fig. 1, these drums are 80 so arranged and the inclination of the trough-like portions is such that the material as it slides therefrom will be caused to travel lengthwise of the drum, and will be advanced into the zone of the next succeeding series of buckets to cause it to be taken up, as rotation of the drum continues, by the 85 buckets in that next series. The construction of the buckets is such that the material therein will not slide out until they have reached substantially uppermost position, and as seen from Fig. 3 when the buckets are in this uppermost position the material which falls from them will drop directly into the water in the bottom of the drum. Unless this arrangement of the buckets is secured the material falling therefrom, even though it is properly advanced, may fall upon the 90 drum, above the water level, where it would be caught up by the next succeeding bucket and carried upwardly without really being moved bodily through the wash water.

In the construction shown the material to be washed is introduced through one end of 95

the drum and is caused to travel throughout the length of the drum being discharged through the opposite end thereof, the wash water, with its load of removed dirt passing 5 out through the same end of the drum through which the material is introduced. The discharge end of the drum is provided with a head 35, attached in any desired manner to the drum, which head is provided, as 10 shown most clearly in Fig. 6 with three openings 36 therein, each of which openings cooperates with one of the buckets in the last series of buckets, the arrangement being such that each of these openings receives the 15 discharge end of its cooperating bucket so that the material discharged from such bucket passes through this opening onto the screen or separator 37. As is usual with such machines a plurality of screens are 20 provided, each succeeding screen having openings therein of decreased diameter so that the material may be properly sized. As shown three screens are provided, the screen 37 having the openings of the largest 25 size desired, the screen 38 having openings of the next smallest size desired and the screen 39 having openings of a still smaller size so that four sizes of material may be thus secured. Conveyor troughs 40 through which 30 the sized material is led away to any desired place are provided, which troughs are shown in a purely conventional manner since they may be of any desired construction. Preferably the head 35 is provided with integral 35 flanges, designated generally by the numeral 41, to which the screens are attached, in any suitable manner, as by means of bolts, as shown. Any other suitable screen mounting may be used. Each of the discharge openings 36 is provided with a curved flange 42, 40 shown in dotted line in Fig. 6, adapted to receive the discharge end of the bucket cooperating with that discharge opening, the purpose of this flange being to prevent the 45 back flow of material from the buckets into the drum, as this material is discharged onto the sizing screens.

The closure member 35 is provided with a centrally arranged bearing member 45, 50 adapted to receive and support a water supply pipe 46. The passage through the bearing 45 is coaxial with the rotary drum 10 so that the drum rotates about the water supply pipe. This pipe 46 extends a considerable 55 distance into the drum 10 and is provided with a plurality of openings 47 through which water is sprayed into the drum. This water is, during operation of the device, continuously introduced, a body 60 of water thus being maintained in the bottom of the drum, the overflow over the lip of the flange 13 carrying out the dirt removed from the gravel. In order to prevent sand, and the like, from working into the 65 bearing 45 and cutting it out, the inner end

of this bearing is provided with a groove 48, the pipe 46 being provided with an opening 49, positioned within this groove, so that during operation of the device water is continuously sprayed into this groove to wash 70 out any sand which tends to accumulate there.

A partition 50, having a centrally arranged opening therein, is provided about midway of the drum to prevent the flowing 75 water from carrying the fine washed sand, in suspension therein, out with the removed dirt.

The drum 10 is provided, adjacent each end, with a ring 55. Each of the rings 55 carries thereon a circular track 56, and a ring gear 57. Suitably attached to the members 21 of the frame are two cross members 58, each of which is provided with upstanding arms 59. Journaled in each pair of the 80 upstanding arms 59, along one side of the frame, is a stub shaft or spindle 60 upon each of which is mounted a combined roller and pinion 61, the roller being flanged and adapted to cooperate with the track ring 56, 85 and the pinion being adapted to mesh with the ring gear 57. Journaled in the two pair of upstanding arms 59, along the other side of the frame is a shaft 62, which has mounted at each end thereof a combined roller and pinion 63, identical in construction with the roller and pinion described. The shaft 62 also has mounted thereon a beveled gear 64, adapted to mesh with a corresponding beveled gear 65 carried upon one end of the 90 drive shaft 66 the other end of which has mounted thereon a pulley constructed for belt drive attachment to some suitable source of power.

As the pulley 67 is rotated from the power source, the shaft 62 is correspondingly rotated and, through the pinions of the members 63 the ring gears at the two ends of the drum are also rotated. Inasmuch as the drum is supported, by means of the 105 track rings 56, upon the roller elements of the members 61 and 63, operation of the shaft 62 will cause rotation of the drum upon these rollers. In practice the rollers sometimes tend to bind or stick, for one 110 reason or another, and as a result sliding, rather than rolling motion, occurs between the track rings and the cooperating rollers. In order to overcome this and to insure rolling contact of these various members each 115 of the drive pinions is rigidly attached to one of the rollers. And in each of the members 61 the roller is rigidly attached to the pinion which meshes with the ring gear and functions as an idler pinion so that 120 these two rollers are also constrained to rotate during operation of the device at the proper speed to insure rolling contact between the rollers and the track members.

The pipe 46, is also provided with a plu- 125

rality of openings 70, within that portion which cooperates with the screens, through which water is sprayed onto the material discharged from the drum to assist in complete separation and screening of such material.

While the form of apparatus herein described constitutes preferred embodiments of the invention, it is to be understood that 10 the invention is not limited to this precise form of apparatus, and that changes may be made in either without departing from the scope of the invention which is defined in the appended claims.

15 What is claimed is:

1. In sand and gravel washers, and the like, the combination with a rotatable drum, having an inlet opening at one end and an outlet opening at the other end thereof; 20 means for introducing into the drum, through the inlet opening thereof, the sand and gravel to be washed and separated; means for continuously supplying water to the drum during operation of the apparatus, to maintain a predetermined quantity of water in the drum; and a plurality of buckets in said drum, arranged in successive series, each of said buckets being open adjacent the shell of the drum and having 25 a baffle member therein so arranged and constructed as to, during rotation of the drum, prevent passage of sand and gravel through said bucket while allowing free 30 passage of water, the end of the bucket remote from the drum shell being formed into an inclined spout, the construction being such that as rotation of the drum carries the bucket through lowermost position in the drum toward uppermost position therein 35 the sand and gravel in advance of the baffle is moved positively through the water in the drum, is carried upwardly within the bucket, and, when the bucket reaches elevated position, is dropped from the baffle into the inclined spout, from which it 40 slides and is advanced into the zone of the next succeeding series of buckets.

2. As an article of manufacture, a bucket 45 for use in sand and gravel washers of that kind in which the sand and gravel is agitated within a body of water maintained in a rotatable drum, said bucket comprising spaced end walls constructed for attachment, at one end, to the interior of the shell 50 of the drum, the other end having attached thereto an inclined spout one end of which is closed by one of the said end walls, the other end being open, and a baffle plate extending between the end plates and so positioned 55 as to allow free passage of water through the bucket adjacent the shell of the drum as the drum rotates but to prevent passage of solid material through said bucket.

60 3. A sand and gravel washer comprising,

in combination, a rotatable drum, having an inlet opening and a separate discharge opening therein, means for introducing sand and gravel, and the like, into said drum, means for introducing water into said drum; and 70 a plurality of buckets mounted within said drum each of said buckets comprising spaced end walls, constructed for attachment at one end to the interior of the shell of the drum and at the other end having attached thereto an inclined spout one end of which is closed by one of the said end walls, the other end being open, and a baffle plate extending between the said end plates and so positioned 75 as to allow free passage of water through the bucket adjacent the shell of the drum, during rotation of said drum, but to at the same time prevent passage of solid material through said bucket.

80 4. In sand and gravel washers, or the like, a rotatable drum constructed to contain the material to be treated, said drum having an inlet opening at one end thereof; an adjustable feeding member having a discharge spout extending through said inlet opening and positioned within the inlet opening end of said drum and pivotal means at each end of said feeding member, said means being capable of concomitant adjustment to vary the angular inclination of the said discharge spout, without substantially effecting the horizontal positioning of the lower end thereof.

85 5. In sand and gravel washers, or the like, a drum constructed to contain the material to be treated, said drum having an inlet opening; a feeding member having a discharge spout positioned within the said inlet opening, the upper end of said feeding member having an arcute slot therein, supporting pins carried by the frame of the apparatus and positioned within the said arcuate slots, and a horizontally adjustable pivotal connection between the lower end of the feeding member and the said frame.

90 6. As an article of manufacture, a bucket for use in sand and gravel washers of that kind in which the sand and gravel is agitated within a body of water maintained with- 100 in a rotatable drum, said bucket comprising spaced end walls constructed for attachment, at one end to the interior of the end of the drum, the other end having attached thereto an inclined spout, one end of which is closed by one of said end walls, the other end being open, and means extending between the end blades and positioned to allow free passage of water through the bucket as the drum rotates but to prevent the passage of the sand and gravel through said bucket.

95 7. A sand and gravel washer of the character described, comprising a rotatable drum, means for supplying the material to be washed through one end of the drum, means for supplying water to the drum, to 110

effect washing of said material, and a plurality of buckets carried upon the inner side of said drum, each of said buckets having an opening therethrough permitting free passage of the water within the drum through the bucket as the drum rotates, and means cooperating with said opening for restrain-

ing the sand and gravel from movement through the bucket at the same time.

In testimony whereof we hereto affix our signatures.

SEBASTIAN A. LOFTUS.
THOMAS CURETON.
